UNITED STATES PATENT OFFICE

124,911

DESIGN FOR A DRESS

William Bass, New York, N. Y.

Application December 5, 1940, Serial No. 97,073

Term of patent 3½ years

To all whom it may concern:

Be it known that I, William Bass, a citizen of the United States, residing at 101 Central Park West, New York city, in the county of New York and State of New York, have invented a new, original, and ornamental Design for a Dress, of which the following is a specification, reference being had to the accompanying drawing, forming part thereof.

I claim:

The ornamental design for a dress, substantially as shown.

WILLIAM BASS.
